UNITED STATES PATENT OFFICE

CLYDE G. PORTERFIELD, OF MARION, OHIO

ROAD MATERIAL SPREADER

Application filed January 29, 1931. Serial No. 512,104.

This invention relates to road material spreaders, and has for one of its objects to provide a novel and highly efficient machine of this character which shall be especially adapted to be used for the purpose of spreading smoothly and according to requirements material applied to highways to level the high crowns thereof or to fill low spots therein.

10 To attain the foregoing and other objects, the nature of which will appear as the description proceeds, the invention comprehends the provision of a road material spreader which shall embody a straight-edge which shall be adapted to ride or slide along the longitudinal center or axis of a highway, front and rear material spreading elements extending laterally from the straight-edge and so angularly related as to 20 form the sides of an isosceles triangle having the straight edge for its base and having its altitude or axis intersecting the transverse center of the straight edge, and a carrier shaft located parallel to the axis of the 25 triangle.

The invention further comprehends the provision of a road material spreader of the character stated wherein the outer or rear end of the front spreading element shall be spaced from the outer or front end of the rear spreading element to provide an opening for the passage of the excess material from the front element to the rear element, and wherein the inner or rear end of the rear element shall be spaced from the straight-edge to provide an opening for the passage 35 of the excess material from the rear element.

The invention further comprehends the provision of a road material spreader of the character stated which shall embody an apron extending forwardly from the outer ends of the front and rear spreading elements and adapted to prevent the material 40 from being spread outwardly beyond the

metal at the edge of the highway, whereby to insure the formation of an even and straight edge.

The invention further comprehends the provision of a road material spreader of the character stated which shall embody a ridge blade extending from the straight-edge rearwardly of the inner end of the rear spreading element and adapted to move the surplus material, passing through the opening at this end of this element, away from the longitudinal axis of the highway so that it will be in the path of the spreading elements when the road material spreader is turned around and again moved over the section of the highway being treated.

The invention further comprehends the provision of a road material spreader of the character stated which shall embody highly efficient means through the medium of which the operator may ascertain from time to time whether the spreading elements occupy the plane necessary to provide the highway with the required crown or elevation, and which shall be adapted to be secured, through the medium of its shaft, to a running gear or other support by means adjustable to maintain the straight edge and blades at the required angle with respect to the horizontal or maintain them horizontally.

The invention is hereinafter fully described and claimed, and illustrated in the accompanying drawings, wherein:—

Figure 1 is a view in side elevation of the spreader applied to a running gear only 80 partly shown.

Figure 2 is a top plan view of the spreader.

Figure 3 is a sectional view taken on the vertical plane indicated by the line 3—3 of Figure 1.

Figure 4 is a view in side elevation of the outer portion of the spreader.

Figure 5 is a sectional view taken on the vertical plane indicated by the line 5—5 of Figure 2.

Figure 6 is a sectional view taken on the vertical plane indicated by the line 6—6 of Figure 2.

Figure 7 is a sectional view taken on the vertical planes indicated by the line 7—7 of Figure 2, and

Figure 8 is a sectional view taken on the vertical plane indicated by the line 8—8 of Figure 2.

10 The road material spreader comprises a straight-edge 1 which preferably consists of an I-beam, and which is adapted to ride or slide along the longitudinal center or axis of a highway. The front end 2 of the straight-edge 1 is curved upwardly and forwardly to prevent it from gouging the highway and thus insure the free riding or sliding movement of the straight-edge. The straight-edge 1 is provided with a shoe or runner 3 which extends throughout the entire length thereof and which is secured thereto by bolts 4 having their heads counter sunk in the lower side of the shoe.

Spreading elements or blades 5 and 6 for 25 the material used to reduce the high crown of a highway or to fill low spots in a highway, extend from the straight-edge 1 in the direction of one edge of the highway. The front spreading element 5 extends outwardly and 30 rearwardly from the straight-edge, and the rear spreading element 6 extends outwardly and forwardly from the straight-edge. The inner or front end of the spreading element 5 is secured by a bracket plate 7 to the straight-edge 1 forwardly of the transverse center of the latter, and the inner or rear end of the spreading element 6 is secured by a bracket plate 8 to the straight-edge 1 at a point rearwardly beyond the transverse center of the latter. The spreading elements 5 and 6 are secured to the straight-edge 1 at equally spaced points from the transverse center of the latter, and the spreading elements are so angularly related as to form the sides of an 45 isoscles triangle having the straight-edge 1 for its base and having its altitude or axis coincident with the transverse center of the straight-edge.

The outer or rear end of the spreading element 5 is spaced from the outer or front end of the spreading element 6 to provide an opening 9 for the passage of the excess material from the spreading element 5 to the spreading element 6, and the inner or rear end of the spreading element 6 is spaced from the straight-edge 1 to provide an opening 10 for the passage of the excess material rearwardly beyond the spreading element 6. The outer ends of the spreading elements 5 and 6 55 are connected together and held in proper spaced relation by a bracket 11.

The spreading element 5 comprises a mold-board 5a and a blade 5b, and the spreading element 6 comprises a moldboard 6a and a blade 6b, the moldboard and blade of each

spreading element being curved transversely and having their concave sides arranged foremost. The moldboards 5a and 6a extend from a plane located above and parallel to the upper side of the straight-edge 1 to a plane located between and parallel to the upper and lower sides of the straight-edge. The blades 5b and 6b extend downwardly from the moldboards 5a and 6a to a plane coincident with the lower surface of the shoe or runner 3.

To insure the spreading of the material smoothly and according to requirements, the spreading elements 5 and 6 are angularly related with respect to each other and to the straight-edge 1 in the manner stated, and these parts are suspended from a running gear or other suitable support through the medium of a shaft 12 which is arranged with its longitudinal axis coincident with the axis of the triangle formed by the spreading elements and straight-edge.

The shaft 12 has angular ends, the outer end thereof passing through an angular opening 13 in the bracket 11, and the inner end thereof passing through an angular opening 14 in a bracket 15 secured to and extending upwardly from the straight-edge 1. As the ends of the shaft 12 and the openings through which they pass are angular, the straight-edge 1 and spreading elements 5 and 6 are held against any rocking movement on the shaft.

An apron 16 extends forwardly beyond the outer ends of the spreading elements 5 and 6, and is secured to said end of the spreading element 6 by brackets 17 and 17a. The apron 16 serves to prevent the material from spreading farther than the edge of the metal of the highway to the end that the highway will be provided with an even and straight edge. A brace 18 extends from a point near the outer end of the spreading element 5 to a point near the front end of the apron 16, and serves to prevent any lateral movement of the apron.

A brace yoke 19 has its cross bar 19a positioned upon and secured at its center to the bracket 15, and has its arms 19b secured to the upper side of the straight-edge 1. Braces 20 extend from the lower ends of the bracket 15 to the ends of the yoke cross bar 19a. A brace 21 is secured to the inner end of the spreading element 5 and to the yoke cross bar 19a, and a brace 22 is secured to the inner end of the spreading element 6 and to the yoke cross bar.

A ridge blade 23 is secured to the straight-edge 1 rearwardly of the opening 10 between the straight-edge and the inner end of the spreading element 6. The ridge blade 23 inclines outwardly and rearwardly from the straight-edge 1, and is adapted to move the surplus material, passing through the opening 10, away from the longitudinal axis of the highway so that it will be in the path of the

spreading elements 5 and 6 when the road grader is turned around and again moved over the section of the highway being treated.

The running gear for the road material spreader may comprise a frame 24, front or steering wheels, not shown, and rear wheels one only of which is shown and designated 25. The running gear may be pulled by a tractor or propelled by a motor mounted thereon and connected to its rear wheels. The running gear further comprises draw bars 26 which are located below the frame 24 and which are connected at their front ends to the frame for rocking movement about horizontal axes, not shown, extending transversely and longitudinally of the running gear. The rear ends of the draw bars 26 are supported from the frame 24 by angle levers 27 and links 28. The angle levers 27 are pivotally connected to a shaft 29 mounted on the frame 24, and the links 28 are connected to the draw bars 26 and to corresponding arms of the levers. Means by which the draw bars 26, from which the machine is suspended, may be swung about their transverse pivot so as to raise and lower the machine, or by which the draw bars may be swung about their longitudinal pivot so as to position the lower edges and the straight-edge 1 and the spreading elements 5 and 6 in the plane necessary to provide the highway with the required surface, are connected to the other arms of the levers 27, and are under the control of the operator located in the cabin, not shown, which may be mounted upon the rear end of the running gear. As the running gear, the steering and operating mechanism therefor, and the lever adjusting means, may be of any well-known or appropriate construction, a further illustration and description thereof are deemed unnecessary.

The road material spreader is suspended through the medium of its shaft 12 from the draw bars 26. The means for suspending the road material spreader from the draw bars 26 comprises a sleeve 30 mounted upon the shaft 12 between the brackets 11 and 15, spacing blocks 31 positioned between and contacting with the sleeve and draw bars, filler blocks 32 secured to the draw bars, and U-bolts 33. A pair of the U-bolts 33 is provided for each of the draw bars 26, and the U-bolts of each pair are located at opposite sides of each draw bar and the blocks 31 and 32 associated therewith. The U-bolts 33 surround the sleeve 30 and pass through clamp plates 34 resting upon the filler blocks 32. Braces 35 extend from the sleeve 30 to the draw bars 26, and serve to hold the sleeve, together with the carrier shaft 12 for the spreader, against any forward or rearward movement with respect to the running gear.

A standard 36 secured to the apron 16, and a standard 37 secured to the brace yoke 19, extend to a plane located between the running

gear frame 24, and draw bars 26, and are provided with longitudinal rows of openings 38. A bar 39 to which a spirit level 40 is secured at a point between the ends thereof is located between and extends transversely of the running gear frame 24 and draw bars 26, and is secured at its ends by bolts 41 to the standards 36 and 37. The spirit level 40 is secured to the rear side of the bar 39 so as to render it clearly visible to the operator stationed in the cabin on the running gear. The lower side of the straight-edge 1, and the lower edges of the spreading elements 5 and 6, occupy a plane which may be horizontal or at an angle to the horizontal, depending upon whether the highway is to be provided with a level or slanting surface, and the spirit level 40 enables the operator to adjust the road grader on the running gear to position the lower side of the straight-edge and the lower edges of the spreading elements in the required plane, and also enables the operator to maintain said side and edges in such plane.

The bar 39 occupies a horizontal position whether the lower side of the straight-edge 1 and the lower edges of the spreading elements 5 and 6 are in a horizontal or inclined plane, and the provision of the standards 36 and 37 with longitudinal rows of openings for the reception of the bolts 41 enables the bar to be horizontally arranged when said side and edges are in an inclined plane, the spirit level 40 enabling the bar 39 to be readily arranged in a horizontal position. With the bar 39 in this position the operator will readily notice any movement of the lower side of the straight-edge 1 and the lower edges of the spreading elements 5 and 6 from their required working plane.

In practice, the material to be used for the purpose of reducing the high crown of a highway or for the purpose of filling low spots in the highway, which material may be bituminous macadam, traffic bound or the like, is dumped on the highway in advance of the road grader. The movement of the spreader along the highway with its straight-edge 1 in alinement with the longitudinal axis of the highway, results in the material being spread first by the spreading element 5 and thereafter by the spreading element 6. The front spreading element 5 causes the material to flow forwardly and outwardly along the surface of the highway. The surplus material passes from the front spreading element 5 by way of the opening 9 into the path of the rear spreading element 6 which spreads it forwardly and inwardly of the highway. The surplus material passes from the rear spreader 6 by way of the opening 10 into the path of the ridge blade 23 which moves it away from the longitudinal axis of the highway so that it will be in the path of the spreading elements 5 and 6 when the spreader is turned around and again

moved over the section of the highway being treated.

Due to the angular relation of the straight-edge 1 and spreading elements 5 and 6, due 5 to the fact that these parts are rockable about their carrier shaft 12 which extends transversely of the highway, and due to the fact that the working plane of these parts may be varied, the material will be spread smoothly 10 and according to requirements.

The straight-edge does not serve as a runner or shoe upon which the machine slides, the machine being carried or propelled by the wheeled vehicle or running gear upon 15 which it is mounted. The straight-edge is of considerable length and may extend both forward and rearward of the vehicle so that it serves to test the evenness of the road surface. The machine is designed primarily 20 for use in crown elimination in which work a road which is relatively too high in the center is built up on the sides. The spreaders are set at the required angle to the horizontal or transversely tilted by adjusting the standards 36 and 37, the spirit level enabling the operator to note any departure from the set position so that the proper corrections can be promptly made. The road material having been dumped in advance of the spreader 25 5, the machine is drawn along the road with the straight-edge traveling on the crown and, by reason of its length, maintaining the spreaders in proper position to effect an even spread of material irrespective of the position 30 of the wheels of the running-gear. The machine may be advantageously used for finishing or balancing sub-grades as the straight-edge will not permit gouging of the surface. The apron 16 prevents loss of material from the front spreader and feeds it to the rear spreader which is very desirable in finishing rough berms or shoulders but if it appears that there is more material than is needed to obtain a perfect shoulder, the 35 40 45 apron may be removed and the surplus material permitted to roll over the side slope into the ditch.

While I have described the principle of the invention, together with the structure 50 which I now consider the preferred embodiment thereof, it is to be understood that the structure shown is merely illustrative and that such changes may be made, when desired, as fall within the scope of the invention 55 as claimed.

What is claimed is:—

1. A road material spreader comprising a straight-edge for lengthwise sliding movement along the longitudinal axis of a road, a 60 rearwardly inclined front blade and a forwardly inclined rear blade secured to the straight edge and extending outwardly therefrom in converging relation, the straight edge extending forwardly and rearwardly beyond the inner ends of the blades, a carrier shaft 65

arranged parallel to the axis of the triangle formed by the straight-edge and blades, means securing one end of the shaft to the straight-edge, means securing the other end of the shaft to the blades near the outer ends 70 of the latter, and means for suspending the shaft from a carrier.

2. A road material spreader comprising a straight-edge for lengthwise sliding movement along the longitudinal axis of a road, 75 a rearwardly inclined front blade and a forwardly inclined rear blade secured to the straight-edge and extending outwardly therefrom in converging relation, the straight edge extending forwardly and rearwardly 80 beyond the inner ends of the blades, the outer end of the front blade being spaced from the corresponding end of the rear blade and the inner end of the rear blade being spaced from the straight-edge to provide excess material 85 discharge openings, means connected to the blades for maintaining their outer ends in fixed spaced relation, a carrier shaft arranged parallel to the axis of the triangle formed by the straight-edge and blades and secured at its outer end to said means, means securing the inner end of the shaft to the straight-edge, and means for suspending the shaft 90 from a carrier.

3. A road material spreader comprising a 95 straight-edge for lengthwise sliding movement along the longitudinal axis of a road, a rearwardly inclined front blade and a forwardly inclined rear blade secured to the straight-edge and converging outwardly 100 therefrom, the straight-edge extending forwardly and rearwardly beyond the inner ends of the blades, the outer end of the front blade being spaced from the corresponding end of the rear blade and the inner end of the rear blade being spaced from the straight-edge to provide excess material discharge openings, 105 means connected to the blades for maintaining their outer ends in fixed spaced relation, a carrier shaft arranged parallel to the axis of the triangle formed by the straight-edge and blades and secured at its outer end to said means, means securing the inner end of the shaft to the straight-edge, and an apron 110 extending forwardly from the outer end of the rear blade.

4. A road material spreader comprising a straight-edge for lengthwise sliding movement along the longitudinal axis of a road, a rearwardly inclined front blade and a forwardly inclined rear blade secured to the straight-edge and converging outwardly 115 therefrom, the straight-edge extending forwardly and rearwardly beyond the inner ends of the blades, the outer end of the front blade being spaced from the corresponding end of the rear blade and the inner end of the rear blade being spaced from the straight-edge to provide excess material 120 discharge openings, means con- 125

nected to the blades for maintaining their outer ends in fixed spaced relation, a carrier shaft arranged parallel to the axis of the triangle formed by the straight-edge and blades 5 and secured at its outer end to said means, means securing the inner end of the shaft to the straight-edge, an apron extending forwardly from the outer end of the rear blade, and a brace extending from the front blade 10 to the apron.

5. A road material spreader comprising a straight-edge for lengthwise sliding movement along the longitudinal axis of a road, a rearwardly inclined front blade and a 15 forwardly inclined rear blade secured to the straight-edge and converging outwardly therefrom, the straight-edge extending forwardly and rearwardly beyond the inner ends of the blades, the outer end of the front blade 20 being spaced from the corresponding end of the rear blade and the inner end of the rear blade being spaced from the straight-edge to provide excess material discharge openings, means connected to the blades for maintaining their outer ends in fixed spaced relation, a carrier shaft arranged parallel to the axis of the triangle formed by the straight-edge and blades and secured at its outer end to 25 said means, means securing the inner end of the shaft to the straight-edge, and a ridge blade extending outwardly and rearwardly from the straight-edge rearwardly of the rear blade.

6. A road material spreader comprising a straight-edge for lengthwise sliding movement along the longitudinal axis of a road, a rearwardly inclined front blade and a forwardly inclined rear blade secured to the straight-edge and converging outwardly 40 therefrom, the straight-edge extending forwardly and rearwardly beyond the inner ends of the blades, a carrier shaft arranged parallel to the axis of the triangle formed by the straight-edge and blades, means securing one 45 end of the shaft to the straight-edge, means securing the other end of the shaft to the blades near the outer ends of the latter, standards secured to the straight-edge and to the outer end of the rear blade, a cross bar carried by the standards, and a spirit level carried by the cross bar.

7. A road material spreader comprising a straight-edge for lengthwise sliding movement along the longitudinal axis of a road, a 55 rearwardly inclined front blade and a forwardly inclined rear blade secured to the straight edge and converging outwardly therefrom, the straight-edge extending forwardly and rearwardly beyond the inner ends 60 of the blades, a carrier shaft arranged parallel to the axis of the triangle formed by the straight-edge and blades, means securing one end of the shaft to the straight-edge, means securing the other end of the shaft to the 65 blades near the outer ends of the latter, a

running gear, a sleeve loose on the shaft, and suspending means connecting the sleeve to the running gear.

8. A machine for spreading road material comprising a single runner adapted to slide 70 lengthwise on the road, and spreader blades carried thereby and extending over the road and converging towards the side of the road.

9. A machine for spreading road material comprising a straight-edge, spreader blades 75 secured to and converging laterally from the straight-edge, the outer end of the rear blade extending outwardly beyond the outer end of the forward blade, an apron secured to and extending forwardly from the outer 80 end of the rear blade, and a bracket rigidly connecting the forward portion of the apron with the outer end of the forward blade.

10. A machine for spreading road material comprising a straight-edge, spreader blades 85 secured to the straight-edge and converging laterally therefrom, the outer end of the rear blade projecting outwardly beyond the outer end of the forward blade and the inner end of the rear blade having its lower edge terminating short of its upper portion and the straight-edge, and a bracket rigidly connecting the outer ends of the blades.

11. A machine for spreading road material comprising a straight-edge, spreader blades 95 secured to and converging laterally from the straight-edge, the outer end of the rear blade projecting outwardly beyond the outer end of the forward blade, means rigidly connecting the outer ends of the blades to maintain 100 them in fixed spaced relation, standards on the straight-edge and at the outer end of the rear blade, a cross bar having its ends connected to the respective standards and adjustable vertically thereon, and a level carried by said cross bar.

12. A machine for spreading road material comprising a straight-edge, spreader blades secured to and converging outwardly from the straight-edge, the outer end of the rear blade extending outwardly beyond the outer end of the forward blade, a bracket rigidly connecting the outer ends of the blades, a bracket on the straight-edge, a shaft mounted in said brackets and held against relative 110 turning, a sleeve encircling the shaft, draw bars, and means engaged with the sleeve for suspending the blade and straight-edge from the draw bars.

13. A machine for spreading road material comprising a straight-edge, spreader blades 120 secured to and converging laterally from the straight-edge, the outer end of the rear blade extending outwardly beyond the outer end of the forward blade, connections between the outer ends of the blades to maintain them in fixed spaced relation, a carrier shaft fixed at one end in said connections and at the opposite end on the straight-edge, draw bars above the shaft, a sleeve around the shaft, spacers 125 130

between the sleeve and the draw bars, and securing devices at the sides of the spacers and draw bars engaged under the sleeve whereby the spreading machine will be suspended from the draw bars and may rock as a unit about the shaft.

In testimony whereof I hereunto affix my signature.

CLYDE G. PORTERFIELD.
